UNITED STATES PATENT OFFICE.

HENRY H. NORRINGTON, OF WEST BAY CITY, MICHIGAN.

MANIFOLDING-BOOK.

SPECIFICATION forming part of Letters Patent No. 789,290, dated May 9, 1905.

Application filed April 27, 1904. Serial No. 205,068.

To all whom it may concern:

Be it known that I, HENRY H. NORRINGTON, a citizen of the United States, residing at West Bay City, county of Bay, State of Michigan, have invented a certain new and useful Improvement in Manifolding-Books, of which the following is a specification, reference being had to the accompanying drawings, which form a part of this specification.

10 My present invention has for its object a novel manifolding-book; and it consists of the construction hereinafter described and claimed, and illustrated in the accompanying drawings, in which—

15 Figure 1 is a view in plan, showing the cover open. Fig. 2 is a view in side elevation, showing the cover open. Fig. 3 is a view similar to Fig. 2, showing portions of the construction and a page in folded position ready to 20 receive the inscription. Fig. 4 is a detail view, in side elevation, showing a modification of the device. Fig. 5 is an additional view showing another modification.

25 My invention is designed to provide a manifolding-book of superior efficiency and utility whereby plural copies may be made of any given entry, one on a permanent bound slip or section, the original memoranda, and one carbon copy thereof, being separable one from 30 the other and from the bound carbon copy. The book consists of record-sheets of any desired number, (indicated at *a*,) each of said sheets being provided with weakened lines, (indicated at *b b*,) dividing the sheet into plural record-sections, (indicated by the numerals 1, 2, and 3.) For certain purposes the sheets might be divided only into two record-sections to provide one carbon impression besides the original, and for certain other pur-

35 poses it will be desirable to divide it into three record-sections, so that two carbon impressions may be made beside the original. The book may or may not be provided with a cover. A cover is shown in the drawings consisting of 40 a lower cover portion *c* and an upper or folding portion *d*. All of the sections 1 of each of the sheets are bound together at the lateral margins thereof, as at *e*, the said sections being bound together along a line parallel to the 45 weakened lines. Intermediate the upper and lower edges of the record-sections 1 and 2 the

sheets are slotted, as indicated at *e*, the slits being provided on the weakened line between the sections 1 and 2 and constituting a part of said weakened line. Carbon-paper, as a carbon-sheet, is indicated at *f*, folded intermediate its edges, forming a pair of leaves, the folded portion being extended through the slits *e*, the folded edge being secured in position in any suitable manner. In Figs. 2, 3, 55 and 4 the folded edge is shown passed through the slits of all the record-sheets and secured upon the cover portion, as indicated at *g*. In books of considerable thickness it will be desirable to have several pairs of carbon-sheets 60 so secured in place, two pairs being indicated in Fig. 3. It is also obvious that instead of a folded carbon-sheet constituting a pair of leaves having its folded edge extending through the slits of the record-sheets two 65 separate carbon-sheets might be provided having their inner edges similarly located and arranged. When arranged, the two carbon-sheets may be folded over the sections 1, 2, as 70 shown.

75 In operation the outer record-section 3 of each record-sheet is first folded over section 2 with the intervening carbon-sheet, the two sections 2 and 3 then being folded again over the permanent bound section 1 with the carbon-sheets, the one lying between sections 1 and 3 and the other between sections 2 and 3, as indicated in Fig. 3 of the drawings. It will be obvious that when so folded section 2 will be uppermost and that the original memorandum is made upon section 2 and carbon 80 impressions are made upon sections 1 and 3 of the record-sheets. To accomplish this result, one carbon-sheet has a carbon-face lying down toward section 1, and the other carbon-sheet lying upon section 2 when folded has a carbon-face lying against section 3. Sections 2 and 3 are then unfolded and detached. One sheet of the carbon will then fall back over section 2 of the underlying record-sheet, 85 and by raising or folding over the record-section 1, upon which an impression has just been made, the other carbon-sheet will fall back into place upon the next record-section 1 of the underlying record-sheet ready for additional memoranda. The sections 1 being 90 permanently bound at their lateral margins 95

parallel with the weakened lines are thus held permanently in place. In this manner each of the sections 1 and 2 have their own carbons, while the slits mentioned afford more ready detachment of sections 2 from sections 1. The bound sections as so arranged lie in a natural and proper position. No shortened sections are necessary, and the record-sheets as so formed and arranged do not require any special cutting-dies for their formation, as would be required if the detached sections were shorter than the bound sections of the record-sheet. The turning back, as already observed, of a bound section lets the carbon-sheet thereon fall into proper place without the necessity of handling the carbon-sheet, and the carbon-sheet also falls into proper place when the detached sections are removed without having to handle the carbon-sheet.

20 The manifolding-book embodied in my invention is well adapted for shipping purposes, for sales-books, for telegraph and warehouse blanks, and for other uses.

I have described the bound sections as being secured at their edges on a line parallel to the weakened lines. I would have it understood, however, that I do not limit myself solely thereto, for, as shown in Fig. 5, the bound sections might be bound at their upper ends, the detachable sections being made shorter than the bound record-sections, the carbon copy, however, being engaged between the bound sections and the adjacent detachable sections. So, also, I do not limit myself solely to engaging the carbon-sheet between the bound sections and the adjacent detachable sections.

In Fig. 3 the carbon-sheet is shown fastened to the top of the bottom portion of the cover—as by cement, for example—while in Fig. 5 the carbon-sheet is shown fastened to the under side of the block or cover portion, as by means of staples.

The carbon-sheets, it will be observed, are so located and arranged as to fold in opposite directions.

What I claim as my invention is—

1. In a manifolding-book a record-sheet divided into sections, said sheets slit between said sections, and carbon-sheets secured in the slits between said sections to fold in opposite directions.

2. A manifolding-book formed of a plurality of record-sheets each sheet divided into sections by weakened lines, said sheets being marginally bound together at the edges of corresponding sections on a line parallel to the weakened lines, each sheet formed with a slit between the bound sections and the adjacent sections, and carbon-sheets located in said slits.

3. A manifolding-book comprising a plurality of record-sheets, said sheets being divided into sections by intervening weakened lines, said sheets being bound together at the edges of corresponding sections along a line

parallel to the weakened lines, and formed with slits between the bound sections and the adjacent sections, and carbon-sheets secured in the slits to fold in opposite directions.

4. A manifolding-book of the nature described formed of a plurality of record-sheets divided into sections by weakened lines, said sheets being bound together at the edges of corresponding lateral sections on a line parallel to the weakened lines, the remaining sections of each sheet arranged to fold over the bound section, each sheet formed with a slit between the bound section and the adjacent section, and carbon-sheets secured in the slits to fold in opposite directions.

5. A manifolding-book of the nature described having a plurality of record-sheets divided into sections by weakened lines, said sheets being marginally bound together at the edges of corresponding lateral sections, the remaining sections of each sheet arranged to fold over the bound section and made separable therefrom along the corresponding weakened lines, each sheet formed with a slit between the bound section and the adjacent section, and carbon-sheets located in the slits to fold in opposite directions.

6. A manifolding-book formed of a plurality of record-sheets, each sheet divided into sections by weakened lines, said sheets marginally bound together at the adjacent edges of corresponding lateral sections, and carbon-sheets secured in place between two adjacent sections to fold in opposite directions.

7. A manifolding-book of the nature described having a plurality of record-sheets, each sheet divided into sections by weakened lines, said sheets at the edges of corresponding lateral sections being marginally bound together, the remaining sections of each sheet arranged to fold over the bound section, each sheet formed with a slit between the bound section and the adjacent section, and carbon-sheets secured in the slits to fold in opposite directions, the intermediate section of each record-sheet, when the sheet is in folded position, lying on the outside.

8. A manifolding-book comprising a plurality of record-sheets each having record-sections separated from one another by a weakened line and each sheet having an intervening slit between the sections, corresponding record-sections of said sheets being marginally bound together along a line parallel to said weakened lines and constituting a permanent record, and carbon-paper engaged in the slits between the bound sections and the adjacent sections.

In testimony whereof I have signed this specification in the presence of two subscribing witnesses.

HENRY H. NORRINGTON.
